(57) **CLAIM**

The ornamental design for a sensor adaptor as shown and described.

DESCRIPTION

FIG. 1A is a first front plan view of a sensor adaptor, with exemplary fittings and a sensor to illustrate an intended use environment.

FIG. 1B is a first back plan view of the sensor adaptor of FIG. 1A.

FIG. 2 is a front perspective view of the sensor adaptor.

FIG. 3 is a second front plan view of the sensor adaptor.

FIG. 4 is a second back plan view of the sensor adaptor.

FIG. 5 is a left side plan view of the sensor adaptor.

FIG. 6 is a right side plan view of the sensor adaptor.

FIG. 7 is a top plan view of the sensor adaptor.

FIG. 8 is a bottom plan view of the sensor adaptor.

FIG. 9A is a first front plan view of a second embodiment of the sensor adaptor, with exemplary fittings and a sensor to illustrate an intended use environment.

FIG. 9B is a first back plan view of the sensor adaptor of FIG. 9B.

FIG. 10 is a front perspective view of the second embodiment of the sensor adaptor.

FIG. 11 is a second front plan view of the second embodiment of the sensor adaptor with a cut line illustrated in FIG. 20.

FIG. 12 is a second back plan view of the second embodiment of the sensor adaptor.

FIG. 13 is a left side plan view of the second embodiment of the sensor adaptor with two cut lines illustrated in FIGS. 17 and 18.

FIG. 14 is a right side plan view of the second embodiment of the sensor adaptor.

FIG. 15 is a top plan view of the second embodiment of the sensor adaptor.

FIG. 16 is a bottom plan view of the second embodiment of the sensor adaptor.

FIG. 17 is a cross-sectional view of the second embodiment of the sensor adaptor along line 17-17 shown in FIG. 15.

FIG. 18 is a cross-sectional view of the second embodiment of the sensor adaptor along line 18-18 shown in FIG. 15.

FIG. 19 is an enlarged view of the second embodiment of the sensor adaptor along the encircled with a dashed line in FIG. 18; and,

FIG. 20 is a cross-sectional view of the second embodiment of the sensor adaptor along line 20-20 shown in FIG. 11. The broken lines in the figures show features of the sensor adaptor that form no part of the claimed design.
